UNITED STATES PATENT OFFICE.

HENRY BAILLET BRUCKNER, OF JERSEY CITY, NEW JERSEY.

DOLL STRUCTURE.

Application filed August 24, 1925. Serial No. 51,918.

This invention relates to toy figures or manikins, and has for its primary object to provide a novel device of this kind consisting primarily of a doll or other toy figure 5 provided with means for mounting a telephonic receiver unit in the body thereof.

More particularly, in one embodiment of the invention, I provide the body of the doll with a transversely extending chamber 10 opening upon the front and rear sides of the doll body and within one end of which the telephonic receiver unit is adapted to be inserted. The sounds emanating from said receiver unit have free egress in amplified 15 volume from the other end of said chamber. In this manner, juvenile and bed-time stories such as are being widely broadcasted by wireless or radio may appear to emanate from the doll, and thus be presented in a 20 very realistic manner.

It is another object of the invention to provide a device of the above character which may be applied to dolls of various forms and constructions as now produced in 25 the art without greatly increasing the manufacture or selling costs thereof.

With the above and other objects in view, the invention consists in the improved radio loud speaker, and in the form, construction 30 and relative arrangement of the several parts as will be hereinafter more fully described, illustrated in the accompanying drawing, and subsequently incorporated in the subjoined claims.

35 In the drawing, wherein I have illustrated one simple and practical embodiment of the invention, and in similar reference characters designate corresponding parts throughout the several views,—

40 Figure 1 is a front elevation of a doll provided with my present improvements whereby the doll subserves the purpose of a loud speaker for radio receiving apparatus;

45 Fig. 2 is an enlarged vertical section taken on the line 2—2 of Fig. 1, and

Fig. 3 is a rear elevation as indicated by the line 3—3 of Fig. 2.

In the type of doll which I have selected for purpose of illustration and which 50 is commonly referred to in the art as a "soft body doll", the body consists primarily of a suitable padding material indicated at 5 confined between front and rear walls of fabric designated 6 and 7 respectively. In a doll 55 of this type, the walls 6 and 7 are provided with openings therein of predetermined size

or area and the padding material extending transversely between these openings is removed. A tube 8 preferably of cardboard is then inserted through this transverse 60 opening and the edges of the fabric walls 6 and 7 surrounding the openings therein are suitably attached to the opposite ends of this tube whereby the latter is held in place. This tube is open at its opposite ends and 65 within the front end thereof a relatively short tube 9 also preferably of cardboard is inserted and permanently fixed to the tube 8 by an adhesive or other suitable means. This inner tube 9 likewise is entirely open at 70 its opposite ends and it will be seen that the rear end edge 10 thereof presents an annular shoulder at a point intermediate the ends of the tube 8.

Within the rear end of the tube 8 the 75 telephonic receiver unit 11 is adapted to be inserted. This unit may be of any conventional form purchasable in the open market and is commonly referred to as a head phone receiver, or one of the two receivers 80 provided in head phones used in connection with radio receiving apparatus. This receiver is provided with the usual current conducting wires 12 and the switch plug 13. The annular shoulder 10 above referred to 85 constitutes a stop limiting the inward movement of the receiver 11 into the rear end of the tube 8, thus providing a substantial space between the receiver diaphragm and the front open end of the tube 8, said space 90 constituting a sound box or chamber into which the sounds initially issue and from which they find egress in amplified volume through the front end of the inner tube 9. It will be understood that the casing of the 95 receiver 11 has a more or less tight frictional fit within the tube 8 so that it will not become accidentally displaced therefrom. The front and rear open ends of the tube 8 are covered or concealed by the clothing of the 100 doll, indicated at 14.

While I have above described my present improvements as they will be embodied in a soft body or stuffed doll, it will of course, be apparent that the device may also be incorporated in doll bodies of other construction such as metal or wood. In the latter case, when a solid wood body is used, it will be understood that a transverse opening of suitable area may be bored therethrough and provided with an internal shoulder as the equivalent of the annular shoulder 10 above

referred to for limiting the inward movement of the receiver unit.

From the foregoing description considered in connection with the accompanying drawing, the construction and several advantages of my improved radio loud speaker will be readily understood. Ordinarily, when the device is not in use, the child may play with the doll in the same manner as any ordinary 10 doll of conventional manufacture. When, however, it is desired to use the doll as a loud speaker, as for instance, when bed-time stories or other stories appealing to children are being broadcasted, it is only necessary to detach one of the head phones or receivers 15 from the head band and insert the same beneath the clothing of the doll at the rear side of the body and into the rear end of the transverse chamber or tube 8 until the 20 front end of the receiver casing abuts against the shoulder 10. When the switch plug 13 is then inserted, the sounds from the receiver diaphragm will issue into the tube 9 or the front end of the chamber where they are 25 amplified and finally emitted from the front open end of said chamber through the clothing of the doll. Thus, such radio programs may be rendered more attractive and amusing and also presented in a very realistic 30 manner. However, it will be understood that the novel features of my present improvements might also be applied to other figures than dolls for use on special occasions. Further, while I have herein 35 described a specific embodiment of the several novel features of the device, it will nevertheless, be understood that the same may be incorporated in various other alternative structures, and I accordingly reserve the 40 privilege of adopting all such legitimate changes in the form, construction and relative arrangement of the several parts as may be fairly embodied within the spirit and scope of the invention as claimed.

I claim:

1. In a structure of the class described, a doll having a chamber extending through the body thereof and open at its opposite ends, one of the open ends of said chamber adapted to removably receive a telephonic 50 receiver unit, the remaining portion of said chamber constituting sound amplifying means, and stop means preventing movement of the receiver unit from its inserted position towards the other end of said chamber. 55

2. In a structure of the class described, a figure or manikin having a chamber extending transversely through the body thereof and provided intermediate the ends of said chamber with an annular stop shoulder adapted to limit the insertion of a telephonic 60 receiver unit into one end of said chamber. 60

3. In a structure of the class described, a doll having a body provided with a transverse opening therethrough and an annular shoulder intermediate the ends of said opening, one end of said opening adapted to receive a telephonic receiver unit frictionally 65 engaging the wall of the opening and said shoulder limiting the insertion of said unit 70 into the opening. 70

4. In a structure of the class described, a doll having a tube extending transversely through the body thereof open at its opposite ends and connected to the front and rear 75 walls of the doll body, a second tube secured within the front end of said first-named tube and also open at its opposite ends, the rear end of said second tube presenting an annular stop shoulder and the rear end of 80 said first-named tube adapted to receive a telephonic receiver unit frictionally engaging the wall of said first-named tube and abutting against said annular stop shoulder. 80

In testimony that I claim the foregoing as 85 my invention, I have signed my name hereto.

HENRY BAILLET BRUCKNER.
